UNITED STATES PATENT OFFICE.

ALEXANDER W. STEWART, OF BOSTON, MASSACHUSETTS.

IMPROVEMENT IN FOLDING ROCKING-CHAIRS.

Specification forming part of Letters Patent No. **150,371**, dated April 28, 1874; application filed March 14, 1874.

To all whom it may concern:

Be it known that I, ALEXANDER W. STEWART, of Boston, in the county of Suffolk and State of Massachusetts, have invented an Improved Folding Rocking-Chair; and I do hereby declare that the following, taken in connection with the drawings which accompany and form part of this specification, is a description of my invention sufficient to enable those skilled in the art to practice it.

The invention relates to an improvement in that class of folding rocking-chairs in which each chair is composed of three rectangular frames—a rocker-frame that constitutes the base, a seat-frame jointed to the rear end of said rocker-frame, and a back-frame jointed to the seat-frame at about the center of the side bars of the latter, and having extensions or feet that rest in notches in the side bars of the rocker-frame, the three frames closing together, and the back-frame forming a lever, by which the position of the back and seat may be adjusted relatively to each other and to the rocker-frame. Such a construction is shown in and covered by United States Letters Patent No. 136,099, granted to A. Russell February 18, 1873. With the specific construction shown in said Patent, it is sometimes difficult to hold the back and seat frames when the feet that enter the rocker-notches are dislodged from such notches, there being then no leverage by which to hold the parts in position, and the consequence is that the parts violently fall and collapse, to the injury of the chair, and sometimes of the party using the same.

In my invention I make an independent connection between the back-frame and rocker-frame, so that, when the feet are raised from the notches, such connection forms a fulcrum, by which the parts may be readily held or changed in position.

My invention consists in combining with the respective frames so jointed together a link-connection between the rocker-frame and back-frame.

The drawing represents, in side elevation, the construction embodying my invention.

a denotes one of the rockers of the rocker-frame, the two rockers being connected, to constitute the frame, by cross bars or rungs *b*. *c* denotes one of the side bars of the seat-frame, the two side bars of said frame being connected at the front by a cross-bar, *d*, and jointed at the rear ends to the rear end of the rockers, as shown at *e*. The back-frame, composed of two side bars, *f*, connected by cross-bars *g*, is pivoted to the seat-frame, as seen at *h*, the side bars *f* being in the vertical planes of the rockers *a*. These side bars extend below the seat-frame, and they are pointed at their lower ends, as seen at *i*, to rest in notches *k* in the top of the rockers. The frame being thus pivoted, I connect the rocker-frame and back-frame by side links *l*, or an intermediate link, *m*, or by both. Each of the side links is preferably made with a slot, *n*, through which the connecting-screw *o* passes, to enable the links to yield readily in adjusting the position of the frames, and if the link *m* be employed it is preferably made as a spring for the same purpose.

It will readily be seen that, by the intervention of this connection or additional connection between the back and rocker frames, a leverage is obtained that enables the parts to be closed or adjusted in position without danger of their falling, and with very slight exertion on the part of the user of the chair.

I claim—

1. In combination with the rocker, seat, and back frames pivoted at *e* and *h*, a connecting-link for controlling the movement of the parts, substantially as described.
2. In combination with the rocker, the seat and back frames pivoted at *e* and *h*, and the side connecting-links *l*.

ALEXR. W. STEWART.
